United States Patent Office.

DAVID JONES, OF MACHEN NEWPORT, WALES.

Letters Patent No. 91,023, dated June 8, 1869.

IMPROVEMENT IN WATER-ELEVATORS.

The Schedule referred to in these Letters Patent and making part of the same.

To all whom it may concern:

Be it known that I, DAVID JONES, of Machen Newport, Wales, now temporarily residing in the city, county, and State of New York, have invented a new and improved Mode of Raising Water; and I do hereby declare that the following is a full, clear, and exact description thereof, which will enable others skilled in the art to make and use the same, reference being had to the accompanying drawings, forming part of this specification.

This invention relates to new and important improvements in the method of raising water through a vacuum produced by the condensation of steam; and

It consists in forming a vacuum by means of a flexible bag, which is inflated by steam, which steam is condensed or allowed to escape.

And it also consists in measuring the steam which is discharged into the expandable and collapsible bag, thereby preventing undue pressure therein, as will be hereinafter more fully described.

The accompanying drawing represents an elevation of the machine, the vacuum-chamber and flexible bag being shown in section, and portions of the supply-tube being broken away, in order to show to better advantage the nature and operation of the device.

A is the cistern or fountain.

B is the vacuum-chamber, into which the water is raised, and which contains the flexible bag.

C represents the bag, which is made of rubber, or other flexible water-proof material.

D is the supply-pipe.

This pipe is connected with the chamber B, as seen in the drawing.

It has a check-valve at its bottom end for preventing the return of the water, as seen at e.

F is the discharge-pipe.

G represents a steam-boiler, for generating the requisite quantity of steam.

H is a measuring-vessel, from which the steam is expanded into the bag.

I is the steam-pipe, which conducts steam from the boiler to the vessel H, and from thence to the collapsible bag C.

J is a pipe, by which the steam is discharged from the bag into a condenser, K, which is connected with the cistern A by the pipe L.

It will be seen that there are two pairs of cocks, which are operated by rods, the cocks of each pair being connected together, so that they may be opened and closed simultaneously; the cock m, in the discharge-pipe F, and the cock n, in the steam-pipe I, being one pair, connected by the rod o, and the cock p, in the steam-pipe I, and the cock q, in the steam-

discharge pipe J, connected by the rod r, being the other pair.

When one pair of these cocks is open, the other pair is closed, and *vice versa*.

Steam being discharged into the vessel H, will fill it at boiler-pressure, but the quantity is designed to be so small that when it is expanded into the flexible bag C, it will expand only sufficiently to inflate the bag, and force out any air and water that may be contained in the chamber B.

It will be seen that the bag is inflated and the cock m is opened at the same time.

When the water in the chamber B has thus been forced out, the other pair of cocks is opened, while m and n are closed.

The steam which is not condensed in the bag will escape through the pipe J, while the vessel H will be again filled with steam, as before.

The bag C will collapse, and a vacuum will be formed, more or less complete, in the chamber B, when the water will rise through the pipe D to fill it.

The bag is again filled or inflated as before, and the operation is repeated as long as may be desired.

The advantages of this arrangement are, that by measuring the steam through the vessel H, and expanding it therefrom, high steam is not allowed to enter the bag, consequently there can be no injurious pressure on the bag; and as the steam does not come in contact with the sides of the chamber B, the condensation is slight, and the amount of steam to work the machine is very small.

Steam may be taken from any source, as from a stationary boiler in any other situation, or from a locomotive, when taking in a supply of water at a railroad station.

I claim as new, and desire to secure by Letters Patent—

1. In a device for raising water by a vacuum formed by the condensation of steam, the expandable bag C, in combination with the air and water-tight chamber B, substantially as described, for the purpose specified.

2. The steam-measuring vessel H, in combination with an arrangement of devices for raising water by a vacuum formed by the condensation of steam, or by the discharge of steam, substantially as described, for the purpose specified.

The above specification of my invention signed by me, this 18th day of December, 1868.

DAVID JONES.
